GARMENT CLIP

Nathan L. Solomon, 343 Highview Road,
Englewood, N.J.

Filed Apr. 14, 1959, Ser. No. 55,502

Term of patent 14 years

(Cl. D17—3)

Fig. 1 is a side elevational view of a garment clip, showing my new design.

Fig. 2 is a top plan view thereof.

Fig. 3 is a bottom plan view with parts thereof in section, the section being substantially on the line 3—3 of Fig. 1; and

Fig. 4 is a sectional view taken on the line 4—4 of Fig. 1.

I claim:

The ornamental design for a garment clip, as shown.
